UNITED STATES PATENT OFFICE.

CHRISTIAN SCHAEFER, OF BUFFALO, NEW YORK, ASSIGNOR TO WHITE, WILE & WARNER, OF BUFFALO, NEW YORK, A CORPORATION OF NEW YORK.

DESIGN FOR A FINGER-RING.

45,312.

Specification for Design.

Patented Feb. 24, 1914.

Application filed December 31, 1913. Serial No. 809,740. Term of patent 7 years.

To all whom it may concern:

Be it known that I, CHRISTIAN SCHAEFER, a citizen of the United States, residing at Buffalo, in the county of Erie and State of New York, have invented a new, original, and ornamental Design for Finger-Rings, of which the following is a specification, reference being had to the accompanying drawing, forming part thereof.

Figure 1 is a side elevation of a finger

ring showing my new design. Fig. 2 is a top plan view of the same.

I claim:

The ornamental design for a finger ring, as shown.

CHRISTIAN SCHAEFER.

Witnesses:

THEO. L. POPP,

ANNA HEIGIS.
